JOHN LAKE, OF PHILADELPHIA, PENNSYLVANIA.

DRY-DOCK SYSTEM.

1,272,679.

Specification of Letters Patent. Patented July 16, 1918.

Application filed December 16, 1916. Serial No. 137,320.

To all whom it may concern:

Be it known that I, JOHN LAKE, a subject of the Czar of Russia and a citizen of Finland, residing at Philadelphia, in the county 5 of Philadelphia and State of Pennsylvania, have invented a certain new and useful Improved Dry-Dock System, of which the following is a specification.

The present invention relates to a method 10 and apparatus for docking vessels for repair or like purposes and has for an object to provide a means for expeditiously emptying a dock and utilizing the discharge water to partially fill adjacent docks of the same 15 dry dock system.

In the operation of dry docks, it is the common practice, after a vessel has been floated to position and properly shored, to pump out the water from the dock to leave 20 it in condition for working purposes. This pumping operation forms quite a considerable item in the cost of operating dry docks while the relatively long interval of time consumed is wasted in so far as actual repair 25 or reconstruction of the vessel is concerned.

It is therefore an object of my invention to overcome such disadvantages by eliminating in a large degree the pumping step heretofore necessary and also reducing to a minimum 30 the time required to empty a dock into which a vessel has been floated.

A further object of the invention is to provide a method of docking vessels which is applicable to a system or plurality of dry 35 docks and wherein the discharged water from any dock may be utilized or employed to partially fill a companion dock or one located at another place in the system.

For the purpose of illustrating my invention, I have shown in the accompanying drawings one form thereof which is at present preferred by me, although it is to be understood that the various instrumentalities of which my invention consists can be 45 variously arranged and organized and that my invention is not limited to the precise arrangement and organization of the instrumentalities as herein shown and described.

Referring to the drawings:

50 Figure 1 represents a transverse sectional elevation of a dry dock system embodying my invention.

Fig. 2 is represents an enlarged detail of one form of control valve.

55 Fig. 3 represents a side elevation of the same.

Fig. 4 represents a detail of a modified form of control valve.

Figs. 5, 6 and 7 represent diagrammatically the operation of the docking system in 60 accordance with my invention.

Fig. 8 represents a plan of the system of dry docks shown in Fig. 1 on a reduced scale.

In the drawings, I have shown a system 65 of dry docks comprising three docks, 1, 2 and 3 arranged side by side in the customary spaced relation, though it will be understood in reading this description that this arrangement is only by way of example to explain 70 the operation of my invention and I do not wish to be restricted or limited to the exact number of docks or their relative position. Obviously the method may be employed with substantially any number of dry docks 75 and the details of my system varied to meet the particular requirements.

4 designates the retaining walls and foundation or bed of the docks, here shown as of concrete, though they may be of any 80 suitable type, since the present invention is readily applicable to the ordinary dry dock construction. The dock chambers 1 and 2, in the preferred form of the invention, are connected at suitable intervals with channels or conduits 5 which form a means of communication between the said chambers and serve to transfer water from one chamber to the other as required. Preferably, 85 these conduits enter the respective chambers through the bottom or float of the chamber and terminate at the floor level in order to effectively drain the chamber as will be understood. Each conduit 5 is provided with a gate valve 6, the valve stem 7 90

of which extends upwardly through the earth, concrete or the like and terminates in an operating wheel or lever 8 which is placed at a convenient and accessible location. In the present instance, the valve 6 100 is of the slide type, operating in a suitable guide 9 formed in the inclosing wall and is preferably of larger area than the cross-sectional area of the conduit which it controls. Thus the valve is adapted to with- 105

stand the relatively high water pressure and insure the complete shutting off of one chamber from the other when it is closed. The stem 7 has threaded engagement with the valve 6, so that the latter may be raised 110 or lowered at will. When the valves 6 are closed as in normal condition, the two cham-

bers 1 and 2 are completely cut off or isolated one from the other and either may be filled with water while the other remains empty. In this latter case, the opening of the said valves immediately establishes communication and the water flows from one chamber to the other until the same level is reached in each.

The dock chambers 2 and 3 are similarly connected by the conduits 10 which are respectively controlled by the valves 11 having stems 12 and hand operating means 13 as will readily be understood. As the function and operation of these conduits 10 are the same as those already described for conduits 5 of the chambers 1 and 2, it is thought unnecessary to repeat in detail.

14 designates conduits extending from chamber 1 to chamber 3 and adapted to form 20 a means of communication between the two chambers as will be apparent. Like the conduits 5 and 10, these conduits 14 lead from the bottom of the respective chambers and are preferably located at opposite ends 25 of the chambers to facilitate the flow of water and more quickly lower the water level in the chamber desired. Each conduit 14 has a control valve 15 preferably operated by the respective hand wheels 16 from an exterior location.

In Fig. 4 a modification of the valve operating means is shown wherein the conduit control valve is electrically operated by the motor 17 which has its switch 18 in 35 a convenient location. The valve 19 is otherwise similar to valves 6, 11 and 15 but is equipped with a rack and pinion movement 20 to transmit motion from the motor as will be understood.

40 The operation of the system will be readily understood by reference to Figs. 5, 6 and 7 wherein a series of docks are represented diagrammatically and each figure represents a step in the operation of discharging the water from the dock which has received a vessel.

Referring first to Fig. 5, it will be seen that the dock chamber 1 is full to the sea level and a ship may therefore be floated 50 into position within the chamber, the sea gates closed and the water is then to be withdrawn from the chamber 1. In this figure all of the valves are closed as will be understood. In order to withdraw the 55 water, the valve or valves 6 controlling the conduit 5 leading to chamber 2 are opened while the valve or valves 15 remain closed. Communication is now had between the two chambers 1 and 2 and the water flows by 60 gravity from the one to the other until a common level is reached. This operation lowers the water to a considerable extent in chamber 1 and by this first step practically one-half of the ordinary pumping operation has been eliminated. In the next step

which is to further reduce the water level in chamber 1, the valve or valves 6 are closed, the valve or valves 15 are opened and as the conduit 14 now has free communication with the empty dock chamber 3 there will be a continuation of the gravity flow which still further reduces the level in chamber 1. As there are only three docks illustrated in the present example of the operation of the system, the small quantity of 75 water remaining in chamber 1 must be pumped out by the usual means. The vessel therefore which has entered dock chamber 1 is now in dry dock ready for the repair work and the said chamber 1 is completely cut off from chambers 2 and 3 by the closing of the valves 6 and 15.

Should it now be desired to dock a vessel in chamber 2, the latter is filled to the sea level by admitting water into it in the ordinary manner and after it has reached the normal level, the sea gates are opened, the vessel floated into position, the sea gates closed and the dock is now ready to have the water drawn or pumped out. The first 85 step in this operation is to open the valve or valves 11 to establish communication with the chamber 3, thus allowing a considerable volume of the water in chamber 2 to flow into chamber 3 and after the same level is 95 reached the valve or valves 11 are closed and the balance of the water in chamber 2 pumped out to complete the docking operation. The foregoing operation is substantially repeated for the docking of a vessel in 100 chamber 3, though where as in the illustration just given there are only three docks and two are now holding a ship in dry dock, it will of course be necessary to pump substantially all of the water from the dock 105 chamber 3, though in actual practice there are usually adjacent docks into which the water from this last chamber may be discharged in the manner previously described. In some instances, it may occur that in a 110 series of docks there may be one considerably smaller than another and consequently the volume of water discharged from a small dock will be insufficient to fill a larger dock to a depth sufficiently great to interfere with the repair work which is proceeding upon a vessel in that latter dock. Thus, for example, a large vessel which has had its shell-plates repaired and the work being done is well up on the body of the vessel, the water 115 admitted from a small dock would not rise sufficiently high to interfere with the work being done. It will, of course, be understood that the best results from the use of the system are attained by careful planning of the work to be done on any vessel and the timing of receiving and discharging the vessel. With a large docking system the schedule for receiving and discharging the 120 vessels becomes exceedingly simple and the 130

transfer of water from a filled dock to an empty one by gravity becomes merely a matter of opening and closing the proper conduits. While I have in the present instance shown a pair of conduits between each adjacent pair of chambers, it will be understood that my invention is not limited in any way to the precise number or to the exact location of any such conduits as this is a matter dependent upon level conditions or the particular dock arrangement. It will also be understood that the location of the valves for the several conduits as shown is merely by way of example and I do not wish to be restricted to the exact type shown or the position of the operating means.

It will be apparent that in a large docking system, a considerable number of combinations are possible where the dock chambers are interconnected in accordance with my invention and it is possible to so schedule the operations that one dock may always be flooded and in receiving condition while others are simultaneously ready to discharge a vessel or vessels.

The method of my invention therefore consists of employing gravity as a means to empty or partially empty a flooded dock, then utilizing the discharge water in a companion dock chamber and timing the steps to meet conditions so that the receiving,

floating and discharging of vessels may take place substantially simultaneously.

What I claim is:

1. In a dry-dock system, a plurality of 35 docking chambers for vessels arranged to fill by gravity from a natural level supply, one of said docking chambers being normally open to said supply and the others normally closed thereto and empty, separate conduits 40 affording communication between each two adjacent chambers, an independent auxiliary conduit connecting the end chambers, and means for controlling said conduits.

2. In a dry-dock system, a plurality of 45 docking chambers for vessels arranged to fill by gravity from a natural level supply, one of said docking chambers being normally open to said supply and the others normally closed thereto and empty, separate conduits 50 affording communication between each two adjacent chambers, an independent auxiliary conduit connecting the end chambers, valve means for controlling the first-named conduits, and independent valve means for controlling the independent auxiliary conduit 55 and causing gravity flow from the one end chamber to the other.

JOHN LAKE.

Witness:

ROBERT M. BARR.
